DRIVE FOR CINEMATOGRAPHIC FILMS

André Léon Victor Clément Debrie, Paris, France

Application December 22, 1933, Serial No. 703,650
In France February 9, 1933

1 Claim. (Cl. 271—2.3)

In all cinematographic apparatuses such as cameras, projectors, etc. the films are generally held in contact with the driving feed drums or sprocket wheels by means of movable presser rolls, adapted to be moved away from the tooth-work of the feed drum say through a pivotal motion. Now this universally known arrangement is not without showing serious drawbacks: On one hand in effect it is cumbersome and costly 5 and on the other hand it makes the loading of the apparatus always long and fastidious.

My invention has for its object an arrangement which removes these drawbacks by omitting the usual presser rolls. It consists in holding 15 the film in contact with the feed drum solely through the natural elasticity of the film, the arrangement being such that the forces which urge the film against the toothwork of the drum are greater than those which have a tendency 20 to make it disengage it. In certain cases, this result may be achieved solely by giving the feed drum a suitable size and providing proper directions for the film when it engages and leaves the drum. However it will be more generally necessary to resort to guiding parts and/or stops 25 which prevent the film from disengaging the drum without these parts or stops ever pressing the film positively against the toothwork, so as to allow the free placing of the film against the toothwork. This part or stop may be of any suitable kind: A rectilinear or incurved channel, 30 a set of guiding rollers, etc.

I have shown two forms of execution of my invention by way of example in accompanying 35 drawing wherein:

Fig. 1 is an elevational view of a first form of execution,

Figs. 2 and 3 relate to a second form of execution, Fig. 2 being a side view and Fig. 3 a 40 cross-section along line AB of Fig. 2.

In the form of execution shown in Fig. 1, the film moves over the feed drum 2 in the direction of the arrow 3. In order to allow the natural elasticity of the film to ensure the contact between it and the drum, I dispose in front of the feed drum 2 a roll 4 acting as a stop and provided with flanges such as 5. This roll is freely 45 rotatable around its axis 6. Behind the feed drum 2, I dispose another roll 7 acting as a stop provided with flanges such as 8 and also freely 50 rotatable around its axis 9. The film 1 passes on one hand between the roll 4 and the feed drum 2 and on the other between the drum 2 and the roll 7, this passage being however completely 55 free without the rolls pressing the film positively

against the feed drum. The rolls 4 and 7 which of course do not need to be provided, like the usual presser rolls, with grooves for engagement with the toothworks of the feed drum, are used solely for constraining the film to travel along a path such that it remains in engagement with the feed drum merely through its elasticity. 5

It may sometimes be necessary to provide, as shown for instance in Fig. 1, for the part of the apparatus disposed above the feed drum, in addition to the rolls 4 and 7, a further roll such as 10 10 which ensures in a perfect manner the desired guidance of the film, while reducing to a minimum the frictional resistances.

It is apparent that, by reason of the interval 15 existing between the rolls 4 and 7 and the feed drum 2, it is very easy to load the apparatus without any further manipulation.

In the form of execution illustrated in Figures 2 and 3, the film 11, as it passes out of the magazine-box 12, is driven by the feed roll 13 and then after it has made a loop 14, it enters the channel 15 of the exposure gate. Around the feed drum 13 and concentrically with reference thereto, there is arranged an arcuate channel 16 serving 20 as a stop and extending over part of the periphery of the feed drum. It should be well understood that the film is held against the drum 13 through the action of its own elasticity at the loop 14 and of the tension of the strand 11, the channel 16 25 only preventing the film from falling in case the film strand or side 11 were to slacken to an abnormal extent. In the form of execution shown, the feed drum has a single toothwork 17; the transverse cross-section (Fig. 3) of the channel 30 35 16 has the shape of a U the leg of which on the toothwork side is exactly adjacent to the flange of the feed drum, while the other leg stops at a certain distance from the latter so as to form an arcuate aperture 18 at the periphery of the drum. 40 Under these conditions, it is easy to introduce the film laterally through the aperture 18 until it abuts through its opposite edge against the first leg of the U. The perforations will engage then automatically the toothwork 17. The 45 width of the aperture 18 and the distance separating the bottom of the channel from the periphery of the drum are sufficiently large to allow the easy introduction of the film.

It is obvious that the above described examples have been given only by way of indication and that it is possible in each particular case to resort to the most suitable arrangement of rollers, incurved channels, rectilinear channels, and the like guides or abutments. 50 55

What I claim is:

In a driving device for cinematographic apparatus a driving sprocket drum provided with a single range of sprockets, a guide for the film 5 so disposed that the film is yieldingly applied against the drum, a fixed shield covering at a distance the part of the drum upon which the film is engaged, said shield having in cross section the shape of a 'U' one branch of which is

much longer than the other; the longest branch extending along the flange of the drum which is the nearest to the range of sprockets, the shortest branch ending near the outer surface of the drum on the side opposite to the sprockets, and leaving between said surface and its own edge a narrow space just large enough to allow the film to be engaged on the sprocket drum. 5
